UNITED STATES PATENT OFFICE.

CHARLES SCOTT SNELL, OF LONDON, ENGLAND.

TRANSPORT-VEHICLE.

1,093,889.

Specification of Letters Patent. Patented Apr. 21, 1914.

Application filed June 2, 1913. Serial No. 771,213.

To all whom it may concern:

Be it known that I, CHARLES SCOTT SNELL, residing at London, England, have invented certain new and useful Improvements in Transport-Vehicles; and I do hereby declare the following to be a full, clear, and exact description of the invention, such as will enable others skilled in the art to which it app- pertains to make and use the same.

This invention relates more especially to vehicles used for the transport of articles of unwieldy length and is particularly applicable to the road carriage of aeroplanes.

The invention further relates to vehicles of the kind which are adapted to be drawn by an independent tractor and in which a pair of wheels of the vehicle are capable of being controlled by a handle or similar means operating in connection with chain or like mechanism. The object of this independent movement being to control the vehicle when rounding corners or the like.

This invention provides in some cases for the controlling of the wheels at the rear of the vehicle, and in some cases from the tractor, and also for the operation of the brakes from the same position.

In carrying out my invention in a typical form, I use two wheels attached to a circular frame or appurtenance thereon, with intervening springs of any convenient character, and upon this frame I mount an upper rotating frame which forms the bed of a platform for carrying the load. Revolving about the same center and embracing the wheel frame is a band to which is attached two arms or "shafts" meeting together at an apex carrying a swiveling attachment to the towing car. At this apex or towing ends of the shafts are mounted two horizontal sprocket or chain wheels, each independently operated by worm gearing and these, by chain connection leading respectively to the wheel body and the platform body, admit of either of these bodies being independently adjusted in angularity as regards the mean center line of the shafts. From the back of the towing car by this means either the load can be swiveled to make its over-hanging ends get clear of an obstruction in rounding a corner, or the path of the follower along the road may be varied from that of the tractor and the tendency to cut corners qualified. The brake gear is also worked from the swiveling end on the tractor by applying tension to a chain which

draws a pulley against a concentrically formed bar carried by the wheel frame and attached to crank arms on an axle, the partial rotation of which brings the brakes into play. Stops are placed to limit the relative angularity between the drag bar section and the wheel base.

For negotiating very sharp turns, I may cause the two wheels to be connected by sprockets and chains to a second axle (where the axis of the wheels does not run right from wheel to wheel) by temporarily keying by a suitable clutch, cause the two wheels to revolve in unison, whereby the path they take is unvarying, while, by disconnecting the worm gear that governs the wheel body, the tractor can take a different path of travel, while the follower keeps along the old path. In order to take up a load, such as an aeroplane, the platform may be made to tip to a suitable angle, either by hinging it on its frame or by allowing the shafts to rise.

By such means the maneuvering power and general handiness of the machine is much enhanced, and turnings can be taken of very small radius.

I will now proceed to describe this invention more particularly by reference to the accompanying drawings in which;

Figure 1 is a part sectional elevation of one form of the invention, Fig. 2 is a plan of Fig. 1, with the load platform removed, Fig. 3 shows in plan, detail of circular frame, Fig. 4 is an elevation of Fig. 3, showing in section the nesting of the circular frames. Fig. 5 shows detail of follower pivoting device on tractor, Fig. 6 shows diagrammatically the arrangement of tractor and follower when in use, Fig. 7 shows detail of modified form of follower in which a tubular shaft is used and the control head is rigid, the steering mechanism being totally inclosed. Fig. 7a is a detail view of the leg 95, Fig. 8 shows detail of control head on tubular shaft arranged to swivel sidewise. Fig. 9 shows detail of brake gear as front view of Fig. 8.

Referring to the drawings, a circular frame 1, having spokes 2, connecting it to a hub 3, carries the wheel carriage referred to as a whole as A. The wheel carriage or frame is bolted or riveted to the frame 1 as shown, on both sides. A hollow axle 4, disposed between the wheel frame cheeks 5, accommodates an inner axle 6. This axle 6

carries a pitch chain wheel 7, at either end as shown, one wheel being loose upon the shaft, the other fast.

The wheels 8 are mounted on stub axles 5 9, which project from the radius arms 10, the latter being hinged upon the axle 4. Springs 11 are disposed between the radius arms and the wheel frame parts as shown, shock-absorbing devices being supplemented 10 if required. The wheel frame is provided with a chain race 12 (see Fig. 4) to accommodate chain 13, which is controlled from the head B, described hereafter, for the purpose of causing the wheel frame to pivot 15 about its axis 14.

A belt or band 15 (see Fig. 4) completely surrounds the circular wheel frame 1, and is connected rigidly to the shafts 16 by riveting or other convenient means. The 20 shafts 16 may be as shown in Fig. 2, in which they are in skeleton form, and latticed for strength as at 17, terminating at their apex which carries the head B, or, they may alternatively take the form shown 25 in Fig. 7, in which a tubular one piece shaft replaces the composite frame shaft. Nesting within the wheel frame 1, is the circular platform frame 20, also formed in a similar manner, its hub pivoting upon the pin 14 30 as shown in Fig. 4. This platform frame is provided with a chain race 21 and a cable or chain which is capable of imparting rotation to it from the control head B. The platform itself 22 may be of any desired 35 character and length, but at its fore end it is preferably arranged to bear against a rubber covered roller 23, which is mounted upon the shaft or shafts 16. Hence the 40 wheels and the platform frames are both capable of rotation about their common axis, relatively to each other and to the shaft member. The shaft head B is supported upon a swiveling hinged spring pivot C, the 45 pull of the tractor being transmitted to the follower through the spring buffer D.

In Fig. 1, the head B is shown in section, and it provides for rotating the platform and wheels as well as for applying the brakes. The means of controlling these 50 functions may be as shown, but the invention is not limited to the detail of arrangement when the control head is of a fixed type as at B. The braking arrangement is as follows: The wheel 25 when turned 55 parts motion through intermediate means to the bell crank 26, a cord or chain 27 is attached to this bell crank at its one end, and to a roller carrying bar 28 at its other end. The bar 28 passes through guides 29, 60 the roller 30 contacting with a curved link 31 which is pivoted at either end to the levers 32, keyed to shaft 33 which latter is carried in journals 34 formed in the wheel frame cheeks 5. The levers 32 carry the 65 cords or straps 35 which operate through

the pulleys 36 rods 37 and levers 38, the cam 39 situate between the end cheeks of the usual type of internal expanding brake blocks 40. Should there be an axial turning movement of the wheel frame and the 70 need to apply the brakes at the same time, it is obvious that some equalizing gear is required, or else more braking effect would be applied to one wheel than the other. This is arranged as follows: Apart from the fact 75 that the link 31 is radial to the pivot 14, the cords 35 are passed over pins 41 on bell crank levers 42, disposed upon the brake levers 32, the other ends of the bell crank levers being connected by a cord or chain 80 43. Hence the brake may be applied whatever the position of the wheel frame 1, and the effect on both wheels is equal. For operating the chains for turning the platform and wheel rings 1 and 20 a windlass 85 or pitch chain wheel arrangement is employed, both operated from the head B by means of worms and worm wheels. The worm wheel shafts which carry the chain wheels being disposed the one within the 90 other as shown, either external wheels or cranks 44 being provided for manual operation. The shaft or shafts 16 are hinged at the head B to the swiveling hinged spring pivot device C, see section in Fig. 5. This 95 consists of a socket 45 arranged to swivel, and is attached to the rear part of the tractor; pivoted to this is a swinging hollow cup 46 carrying at its sides gudgeon pins to which is hinged the fork of the buffer rod 100 47. The cup 46 carries a tubular extension 48, whose top end is flanged over as shown. Within this extension is a spring 49 disposed between washer plates 50, and a rod 51 passes through these plates, and is attached to a cap 52, the rod taking a bearing upon the top washer as shown. To this cap is attached the forks of the shaft or shafts 16. This arrangement provides therefore, 105 for vertical motion controlled by the spring 110 49 which is double acting against movements vertically. This also provides for motion backward and forward as controlled by the buffer D (hereinafter referred to) and for the relative angular motion produced between the tractor and follower as when 115 turning corners, owing to the swivel 45 operating on the tractor.

The buffer D is of identical construction to the above but operates horizontally. An 120 application of the same principle is shown in connection with the swiveling head B of the tubular shaft type of follower shown in Fig. 8; in this case the springs of the tractor itself take up the vertical vibrations. 125 It consists of a buffer rod 47 controlled in its movement by an abutment at back and front with a helical spring between. The guides 60 carry the rod 47. The rod is 130 preferably tubular as shown, and carries at

either end tubular abutments 61 and 61'; between these abutments is a coiled spring 62. Hence the abutments are normally in equilibrium but resist motion in both directions. If the follower drags, then the after abutment 61 moves forward, until the resistance of the spring equalizes it. On the other hand, if the follower tends to push the tractor, as when descending a hill, then the fore abutment 61 moves backward against the spring likewise. Hence, it will be clear how the equivalent parts C and D as applied in Fig. 1 comprise double acting buffers against vertical and longitudinal movements.

Figs. 7, 8 and 9 show a slightly modified form of follower, and its parts, in which single tubular shaft 65 replaces the double shaft 16. In this device the steering head 20 B is arranged to swivel so that the operator can control the follower from the side, the motion being transmitted to the platform, brakes, and wheels through bevel or miter gears and sleeves. The arrangement is as 25 follows: The shaft 65 carries the cast head piece B provided with a turned hollow boss 66 recessed into the tube 65; rotative motion between these two parts is controlled by means of the catch device 67, the lock ring 30 68 (which is placed in position in two halves) held by the set screw 69 keeping these parts in place. A tubular pillar 70 is bolted to the head piece B, and this carries within it sleeves 71, 72 and 73, in fast 35 connection with hand wheels 74, 75 and 76 which operate respectively through the miter spur gears 77, 78 and 79, the platform, wheels and brake. The platform and wheels are controlled through the medium 40 of the sleeves 80 and 81 respectively, suitable gearing of a mechanical equivalent to that described under Figs. 1 and 2, being arranged at the rear end to operate the wheels and platform. The brake is operated 45 through the worm 82 disposed on the shaft 83 which carries the miter wheel 77. The worm 82 meshes with worm wheel 84 on shaft 85. The worm wheel carries a cord pulley 86, whose motion tensions the 50 cord 87 to operate the brake mechanism. A seat 90 may be arranged in conjunction with the steering head as shown in Fig. 7, this seat being capable of folding up if required.

The operation of swiveling the head is 55 as follows: The catch 67 is released by withdrawal after removing the safety pin 67^b, which allows the boss 66 to turn within the tubular shaft 65, the hand wheels 74, 75 and 76 being turned to restore alinement or previous 60 position of the brake wheels or platform if desired. By means of catches 67^a formed in the head B concentric with axis of the tubular shaft 65, any desired angle up to say 90° either side of the vertical may 65 be given to the head B. Bushes 92 may be

employed as steady rests for the control sleeves 80 and 81.

The operation of the invention is as follows: The aeroplane or other load to be carried is disposed upon the platform 22, the fore end of the platform resting upon the anti-chattering roller 23. In the arrangement shown in Fig. 7, a leg or legs 95 is or are provided upon which the follower may rest when not attached to the tractor 96, and by means of a rack and pinion arrangement, such as shown in Fig. 7^a, the platform when disconnected from the tractor may be tilted the better to receive its load. When under motion, varying road inclinations produce varying compressions upon the buffer spring 62, while inequalities of the road effect, and are absorbed by, the spring 49. While under motion the platform may be turned to any angle independently of the path of the follower by the means previously described. Again, the wheels may conjointly be moved from the worm apparatus in the steering head as shown in Figs. 1 and 2, or by means of the miter 78 as shown in Fig. 8. When the wheel frame is turned out of alinement with the center line of the shaft, the wheels may be locked as if they were fixed to one axle, for instance, a clutch operated from the control head, may be disposed upon the shaft 6 so as to throw the loose sprocket wheels 7 into driving engagement with the shaft, or a pin 100 may be temporarily put through the sprocket wheel boss in place of a clutch. It is however 100 found in practice that the wheels may be left free on their axles without this refinement of locking, the simple turning of the wheel frame being sufficient for most practical purposes.

The operation of the brake arrangements have been previously described, but it may be pointed out, that the brake arrangements being independent of any of the other control movements, the brakes may be applied when going down hill in order to relieve forward compression of the buffer spring 62. By these means it is obvious that a large and unwieldy load can be carried over any track that is large enough to accommodate the width of the vehicle and its freight, the tractor and follower being capable of turning movements independently of each other, so that the very sharpest corner or bend can be negotiated with ease.

For military purposes, an apparatus of this sort is invaluable, since in negotiating rough country, it frequently happens that corners on unmade roads have to be negotiated, or where a road is much cut up the wheels of the follower may be made to travel parallel to, but at one side of, the track of the tractor. Although the plans show a platform for the carriage of an aeroplane, it is obvious that any other form of body 125

may be attached to the upper swiveling bed such as may be required for ambulance purposes, poles for telegraph purposes or other military requirements. Again, bodies useful for any commercial purpose may be affixed. Such a vehicle can of course be steered if pushed backward, and therefore admits of entry to and retreat from narrow passages, entrances to docks, movement between piles of goods, backing between loading platforms and such like situations where trailers are usually very difficult to operate.

In my description I have shown the trailer or follower attached to an ordinary motor car, but obviously a steam or oil driven tractor may be used, and may instead of being detachable be permanently linked up with the follower. A horse drawn tractor frame may be employed if desired. The exact mechanical construction may obviously be varied without departing from the spirit of my invention.

I claim:—

1. In a truck, the combination, with a wheeled carriage provided at its upper part with a circular frame, of a longitudinal draft member provided with a band at its rear end which is mounted on the circular frame, a circular platform-frame pivoted concentric with the said frame, a platform secured to the platform-frame, means for connecting the front end of the draft member to a tractor, and steering mechanisms mounted on the front end portion of the draft member and operatively and independently connected with the two said circular frames, whereby the supporting carriage and the platform are moved pivotally and independent of each other.
2. In a truck, the combination, with a wheeled carriage provided at its upper part with a circular frame, of a longitudinal draft member provided with a band at its rear end which is mounted on the circular frame, a circular platform-frame pivoted concentric with the said frame, a platform secured to the platform-frame and projecting forwardly over the draft member, an antifriction device supporting the overhanging portion of the platform from the draft member, means for connecting the front end of the draft member to a tractor, and steering mechanisms mounted on the front end portion of the draft member and operatively

and independently connected with the two said circular frames, whereby the supporting carriage and the platform are moved pivotally independent of each other.

3. In a truck, the combination, with a supporting carriage provided at its upper part with a circular frame; an axle carried by the carriage in front of the circular frame, pivoted arms carried by the axle and projecting rearwardly and having axle spindles at their ends, springs arranged between the said arms and the supporting carriage, and road wheels mounted on the axle spindles; of a longitudinal draft member provided with a band at its rear end which is mounted on the circular frame, a circular platform-frame pivoted concentric with the said frame, a platform secured to the platform-frame, means for connecting the front end of the draft member to a tractor, and steering mechanisms mounted on the front end portion of the draft member and operatively and independently connected with the two said circular frames, whereby the supporting carriage and the platform are moved pivotally and independent of each other.

4. In a truck, the combination, with a wheeled carriage provided at its upper part with a circular frame, of a longitudinal draft member provided with a band at its rear end which is mounted on the circular frame, a circular platform-frame pivoted concentric with the said frame, a platform secured to the platform-frame, brakes operatively connected with the wheels of the wheeled carriage, a brake operating mechanism supported in front of the wheeled carriage, intermediate connections between the brake operating mechanism and the said brakes, means for connecting the front end of the draft member to a tractor, and steering mechanisms mounted on the front end portion of the draft member and operatively and independently connected with the two said circular frames, whereby the supporting carriage and the platform are moved pivotally and independent of each other.

In testimony whereof I have affixed my signature, in presence of two witnesses.

CHARLES SCOTT SNELL.
